UNITED STATES PATENT OFFICE.

ALBERT WARD PATTISON, OF LOCKPORT, NEW YORK, ASSIGNOR TO NIAGARA OIL BURNER COMPANY, A CORPORATION OF DELAWARE.

VAPORIZER HYDROCARBON-BURNER.

1,285,352.

Specification of Letters Patent. Patented Nov. 19, 1913.

Application filed February 15, 1913. Serial No. 217,409.

To all whom it may concern:

Be it known that I, ALBERT WARD PATTISON, a citizen of the United States, residing at Lockport, New York, have invented certain new and useful Improvements in Vaporizer Hydrocarbon-Burners, of which the following is a specification.

This invention relates to burners of the type applicable to existing stoves, heaters, 10 and the like, built to use solid fuel such as coal, to convert them into stoves which can use liquid fuel such as kerosene. The object of the invention is to produce a burner for this use which can be readily applied to 15 such stoves, which will have a minimum of weight for the heat it has to withstand, which will be very easy to light, which will thoroughly vaporize the oil, and which will have a wide range of possible temperatures 20 from very low to very high.

The invention is illustrated in the accompanying drawings in which Figure 1 is a plan view of the device. Fig. 2 is a side elevation with parts in section, the section 25 being taken along the line 2—2 in Fig. 1. Fig. 3, is a sectional view taken along the line 3—3 in Fig. 1. Fig. 4, is a bottom view of the dome element.

In the drawings, the numeral 11 indicates 30 a base plate adapted to rest upon the grate of a usual coal or wood burning stove. This plate 11 is provided with a central depression or well 12, from the center of which projects a hollow frusto-conical burner base 35 13, having perforations 14 in its flat upper face. 15 represents a fuel feed pipe from any suitable fuel supply, such as a tank. The pipe 15 passes up through the burner base 13 and enters a distributor head 16 having a central jet orifice 17 therein. The under side of the distributor head 16 has a boss 18 to space the head from the flat top of the burner base 13.

At each end of the base plate 11 are located pairs of openings 19, 20 and 21, 22, each surrounded by a collar 23. Adapted to fit into these openings, is a spider-like dome element 23, having a plurality of downwardly curved legs 24, 25, 26, and 27, merging into a central portion 28 having a bottom opening 29 therein smaller than the leg openings and located directly over the distributor head 16 but spaced therefrom.

In operation, the device is applied to an 55 existing stove, such as a cook stove, by rest-

ing the base plate 11 upon the grate and then connecting the fuel pipe 15 from an oil tank to the base plate and distributor head 16 as shown in the drawings. Fireclay is then placed around the base plate upon the 60 grate so that all the draft from the bottom of the stove, or ashpit, upwardly will be through the tubes of the spider-like dome.

Assuming then that the device has been installed as above outlined, fuel oil is let 65 into the feed pipe 15 from whence it will flow out from the jet 17 and trickle over the distributor 16 down into the well 12. A match applied to this oil will set it on fire which heats the burner base 13 which vaporizes the incoming oil. Flame from the burning oil rises around the legs of the spider-like dome and they become red-hot so that air coming from the ash-pit into them is thereby heated to a high temperature. 70 As the area of the inlet openings, to the legs is six times greater than the outlet 29, the air crowds at the outlet and tends to come out under slight pressure. The outgoing air is sprayed onto the distributor 75 head 16 into the flame which is a circular one so that combustion of the oil takes place around the edges of the distributor 16 from whence it flares up and keeps the dome hot. The flue of the chimney and blast of the 80 flame cause a continuous suction of air from the ash-pit up through the legs of the spider and down through the outlet 29 into the flame. The flame is an intensely white and hot one and I find that I can make it as 85 long as six feet by feeding sufficient oil to the burner. Combustion is so perfect that the flame sparkles brilliantly and there is an entire absence of any puffing. I have found that with this burner, the oven of a 90 cook stove can be raised to and maintained at 900° F. while on the other hand, the burner may be turned down so low as to consume only 54 drops of oil per minute.

What I claim is:

1. A hydrocarbon burner comprising a base, a central oil feed, a distributor over which the oil passes, air tubes through which the draft is drawn from below the grate to the chimney, a relatively large chamber at 105 the juncture of the tubes receiving the air therefrom and constituting an intermediate reservoir between the tubes and the distributor and located directly above the distributor, the chamber having an opening of less 110

diameter than the distributor so as to retard the flow of air, its size and relation to the tubes and to the distributor being such that the flame surrounds and envelops the chamber and the air issuing therefrom is intensely hot, and vaporizes the oil flowing over the distributor producing perfect combustion and preventing carbonization.

2. A hydrocarbon burner comprising an oil feed, a conical distributor element receiv-

ing the oil therefrom, and a spider-like air heating dome located over and above the conical distributor including an air chamber relatively large and having an outlet for heated air directly above the distributor of less diameter than the chamber and the distributor, the heated air being forced downwardly around the distributor to produce an annular flame.

ALBERT WARD PATTISON.
